(57) **CLAIM**

The ornamental design for an interior portion of an automobile, as shown and described.

DESCRIPTION

FIG. 1 is a front left perspective view of an interior portion of an automobile showing our new design;

FIG. 2 is a front right perspective view thereof;

FIG. 3 is a front view thereof;

FIG. 4 is a top view thereof;

FIG. 5 is a bottom view thereof;

FIG. 6 is a left side view thereof;

FIG. 7 is a right side view thereof;

FIG. 8 is a perspective view of one door of the interior portion;

FIG. 9 is a front view of one door of the interior portion;

FIG. 10 is a right side view of one door of the interior portion;

FIG. 11 is a left side view of one door of the interior portion;

FIG. 12 is a top view of one door of the interior portion; and,

FIG. 13 is a bottom view of one door of the interior portion. Our design includes the mirror image of the embodiment depicted.

In the drawings, the broken lines in depict portions of the article that form no part of the claimed design.
